UNITED STATES PATENT OFFICE.

ROBERT F. FOSTER, THOMAS S. BAYLIE, AND JAMES HARBIN, OF WASHINGTON, DISTRICT OF COLUMBIA.

IMPROVEMENT IN MACHINES FOR ROUNDING AND BACKING BOOKS.

Specification forming part of Letters Patent No. 137,192, dated March 25, 1873.

To all whom it may concern:

Be it known that we, ROBERT F. FOSTER, THOMAS S. BAYLIE, and JAMES HARBIN, all of the city and county of Washington, in the District of Columbia, have invented a certain Machine for Rounding and Backing Books, of which the following is a specification:

Nature and Objects of the Invention.

In the operation of binding books, or of manufacturing bound books, the sheets are first sewed together; and the books as thus produced are then cut in square form. The sewed side of each book is then coated with glue to more securely unite the sections and to preserve the final shape of the book; and when this coating is in proper condition—before it becomes perfectly hard or set—the books are passed through the rounding and backing operations. Rounding expresses the production of the concavity of the face or open edge of the book. Backing is the operation of forming the back or closed edge of the book, and includes jointing, which comprises solidifying a book and spreading its back to form the joints or depressions for the reception of the sides or binding-boards. Machinery for backing or jointing books has been used; but the rounding operation has heretofore been practically accomplished only by hand hammering.

This invention relates to a cheapening and labor-saving machine for rounding and backing books at one continuous operation in a rapid and superior manner, the agency employed being rollers applied as hereinafter set forth. The invention consists, primarily, in rounding books by means of a pair of rollers operating in combination with a suitable form or mandrel applied to the faces of the books; secondly, in the employment of changeable rollers and forms for rounding books of different thicknesses; thirdly, in the employment of the said form as a shoulder on a reciprocating feed-table or plunger to introduce the books between pressing-rollers; fourthly, in one or more pairs of pressing-rollers, adjustable as to distance apart, and driven through suitable gearing to receive the books from the rounding mechanism, so as to preserve their form, and to express the air so as to solidify the books; fifthly, in an adjustable clamp arranged to

receive the books from the pressing-rollers, and to hold them during the completion of the backing operation, and in a gage-stop combined therewith to arrest the books in proper position.

Description of the Drawing.

Figure 1 and Fig. 2 are opposite side elevations of a machine for rounding and backing books illustrating this invention. Fig. 3 is a vertical longitudinal section of the same on the line *a a*, Fig. 4, illustrating the rounding operation. Fig. 4 is a plan view, partly in section, on the line *b b*, Fig. 1. Fig. 5 is a vertical longitudinal section of the delivery end of the machine, illustrating the backing operation. Fig. 6 is a similar view, illustrating the application of a stop-gage to the clamp for holding the book during the backing operation.

General Description.

In carrying out this invention a strong frame, *A*, is constructed of any suitable form and materials. The top of this frame is preferably inclined, as represented, the higher end being of suitable height for a standing workman who feeds the machine. The books are discharged at the lower end onto an endless apron, off-bearer, or a receiving-box. The square books are placed, one at a time, on a receiving-table, *B*, which is mounted at the higher end of the frame in longitudinal ways so as to slide back and forth. At the outer end of this table a bracket, *C*, is erected thereon to support a form or mandrel, *D*, which constitutes also a shoulder to adapt the table to operate as a plunger. A pair of rounding-rollers, *E*, are arranged so as to coat with the form *D* during the first part of its forward movement with the table *B*. The continued movement of the table introduces the back edge of the book which is being formed between the first of a series of pairs of pressing-rollers, *F*. These express all air from between the leaves and deliver the rounded and solidified book onto a table, *G*, which, in combination with a parallel jaw, *G²*, constitutes a clamp to hold the book during the completion of the backing operation. A gage-stop, *H*, Fig. 6, arrests the book in proper position. A backing-roller, *I*, is mounted in a frame, *J*, which carries the same back and

forth vertically across the delivery end of the clamp G G^2 to back or joint the book. When this is retracted the book is released and discharged. Attaching-screws z , in combination with slots y , or their equivalents, provide for adjusting the form-bracket C to suit books of different widths. To provide for rounding books of different thicknesses, the form D is adjustable vertically by means of screws x and sliding boxes w , or their equivalent. The form or mandrel preferably consists of a cylindrical roller, the back of which may serve for rounding thin books. An undercut groove in the front of the form receives interchangeable face-plates v of the proper size or shape for any given thickness of book. In the illustration, the rounding-rollers E are supported and guided by pivoted arms u drawn together to hold the rollers in normal position by springs t . Rollers of different sizes are preferably employed for rounding thicker and thinner books. To further adapt these rollers to operate in proper manner, the pivots of their arms u may be adjusted to correspond with the center of the thickness of book being formed, and so as also to vary the radius of the movement of the rollers, if desired, by the employment of graduated series of sockets therefor, and pivot-holes in the arms, as represented, or otherwise. These rounding-rollers operate by coming in contact with the square book at its center, and moving outwardly on the convex back as they round the face of the book against the form D or its face-plate v , as illustrated in Fig. 3. The pressing-rollers F are arranged in two parallel series, the upper of which is movable, to provide for regulating the pressure on books of different thicknesses. These upper rollers may be mounted in a bearing-frame, K , of suitable structure, guided perpendicularly to the inclined plane of the mechanism, and this frame may be supported and adjusted by a central screw-pendant, L , furnished with a hand-wheel, M , for turning it, as represented. The clamp G G^2 is made adjustable, to adapt it to properly hold books of different thicknesses, and to vary its pressing action by means of screws s and slots r , or their equivalent, as means for attaching the upper plate or jaw G^2 to its arms or yokes N , and said slots may serve also to receive guide-lugs q , Fig. 3. The gage-stop H may also be adjustable to vary the projection of the book, which determines the size or depth of joint produced. The backing-roller I is removable, to permit the employment of interchangeable rollers for books of different thicknesses, and is also adjustable in its frame J by means of sliding journal-boxes p , with screw-stems o , beveled gear-nuts n , and a shaft, m , with hand-wheel l and pinions k , for rotating the said nuts in unison, or by any preferred device. The pivot of the backing-roller frame J may also be adjustable correspondingly with the pivot of the rounding-roller arms u and with the center of the thickness of book being formed. These adjustments, or their equivalents, adapt

a given machine to form books of various sizes and thicknesses within certain limits. For larger or smaller books different machines, with like scope, may be employed, the size of the pressing-rollers also being varied, preferably.

The mechanism for operating the various parts admits of considerable modification. In the illustration, (reference being made to the drawing,) S represents a horizontal driving-shaft, transverse to the machine, and O O^2 and P represent tight and loose pulleys and a beveled pinion thereon. S^2 represents a longitudinal shaft on the same side of the machine. (See Fig. 2.) P^2 represents a bevel-gear on the upper end of this shaft, meshing with a driving-pinion, P . P^3 P^4 represent pairs of bevel-gears connecting the lower pressing-rollers F , respectively, to this shaft; and P^5 P^6 represent a pair of bevel-gears, and X^6 X^6 a reversing-train of spur-wheels connecting a transverse shaft, S^3 , to the same. S^4 represents a perpendicular shaft on the opposite side of the machine, (see Fig. 1,) and P^7 P^8 represent bevel-gears connecting the same with the first of the lower pressing-rollers F . P^9 P^9 represent bevel-gears on the projecting shafts of the upper pressing-rollers F ; S^5 , a longitudinal shaft carried by the bearing-frame K of said rollers; and P^{10} P^{10} , pinions thereon to connect the said gears P^9 . P^{11} represents a bevel-gear on the perpendicular shaft S^4 , connected thereto by a spline, and to the bearing-frame K , so as to be raised and lowered therewith, in mesh with the adjoining gear P^9 , to drive the connected upper pressing-rollers. S^6 S^7 S^8 , Figs. 3 to 6, represent shafts parallel to the transverse shaft S^3 . Q R , Fig. 1, represent a cam and a spur-sector on the outer end of the shaft S^3 , and T a crank-arm on the corresponding end of shaft S^6 . U represents a yoke-slide engaged by the cam Q , and V a link connecting this slide to the crank-arm T . An intermittent rocking motion is thus imparted to the shaft S^6 . T^2 represents a second crank-arm on this shaft, and V^2 a second link connecting this arm to the delivery-table G , to slide the same back and forth. W represents a rod connecting the delivery-table G and feeding-table B , so that they move in unison. X X^2 represent spur-wheels connecting the shafts S^3 and S^7 , and Q^2 Q^2 represent cams on the latter shaft. N^2 represents a bar trunnioned in the lower ends of the yokes N , to which the plate or jaw G^2 of the clamp G G^2 is attached. i represents a second trunnioned rod; h h , journal-brackets supporting the same; and g , arms projecting therefrom through the rod N^2 , to support the latter against turning on its axis, and to guide the lower ends of the yokes N . f f represent steel blocks applied to the bar N^2 , to engage with the cams Q^2 , by the action of which the jaw G^2 is drawn down to compress and hold the book during the completion of the backing operation. f^2 f^2 represent incased springs or cushions beneath the blocks f , to furnish a yielding support thereto. By this provis-

ion, in case one or more extra sections are introduced, so as to increase the thickness of a book beyond that for which the parts are adjusted, the clamp will yield, and the breakage which might otherwise result is thus obviated. Similar cushions may be introduced elsewhere in the machine. Y represents a spring for elevating the jaw G² when it is released. X³ represents a spur-wheel on the shaft S⁹ to engage with the spur-sector R, and T³ T⁴, Figs. 1 and 6, represent cranks—the latter a disk-forming parts of said shaft.

Referring to Fig. 6, e represents a hanger depending from the delivery-table G, and Z represents a lever pivoted thereto and embracing the wrist of the crank T³. S⁹ represents a shaft, to which the gage-stop H is attached, and X⁴ represents a pinion thereon. R² represents a rack on the under side of the table G to engage with this pinion X⁴. d represents one of a pair of slotted bearings to support and guide the shaft S⁹. V³ represents a link connecting the shaft S⁹ to the upper end of the lever Z. The object of this mechanism is to cause the stop H to advance to the position represented in full lines in Fig. 6 at the proper moment to arrest a book until the clamp G G² closes thereon, and then to withdraw the stop before the backing-roller I. The stop, as thus retracted and as carried back with the table G, is represented, with its appurtenances, by dotted outlines in the figure.

Referring again to Fig. 1, X⁵ represents a spur-wheel attached to the frame J of the backing-roller I, concentric with its axis, and R³ a spur-sector engaging therewith. T⁵ represents a crank or lever arm attached adjustably to the spur-sector R², and V⁴ a link or pitman correspondingly attached to the extremity of this arm to connect it with the crank-disk T⁴. c represents a slot; c², a screw; and c³, perforations to constitute adjustable connections between the arm T⁵ and sector T⁴ and between the said arm and the link V⁴, to regulate the movements of the backing-roller.

The operation of the machine as a whole, considered briefly, is as follows: A constant rotation is imparted to the pressing-rollers F and proper intermittent motions to the feeding and delivery tables B G and to the clamp-jaw G², stop H, and backing-roller I. A square book placed on the feeding-table B is first acted on by the rounding mechanism and then fed between the pressing-rollers F. Simultaneously the delivery-table G receives a rounded book from the pressing-rollers F, carries it to the stop H, and then, in connection with the clamping-jaw G², holds the book securely for a certain period, during which the backing-roller I operates, the stop H reced-

ing before it. Finally, the clamping-jaw G² is elevated, and, the stop H being in retracted position, the released book is discharged. The feeding and delivery tables then make their return movement, the former to receive another square book and the latter to receive the rounded book which was received by the feeding-table at the beginning of the operation, and which has been pressed, meanwhile, by the rollers F.

The delivery-table G may be stationary and other details of the machine may be varied. The operating parts being inclined, as shown and described, the machine is adapted to feed automatically.

If preferred, the mechanism may be arranged in a horizontal plane.

Claims.

The following is claimed as new:

1. The rounding-rollers E, operating substantially as herein described, in combination with a form or mandrel and a supporting table or holder, for the purpose specified.
  2. The combination of changeable rollers and forms or mandrels for rounding books of different thicknesses.
  3. The rounding form or mandrel D erected on the feeding-table B to operate in connection therewith to introduce the books between the pressing-rollers, substantially as set forth.
  4. The pressing-rollers F, in combination with the rounding-rollers E, for receiving the rounded books so as to preserve their form, and for expressing the air so as to solidify the books, as set forth.
  5. The clamp G G², arranged and operated substantially as described, in combination with the pressing-rollers F and backing-roller J, for holding the rounded books during the backing operation.
  6. The stop-gage H, arranged and operating substantially as described, for the purpose specified.
  7. The combination of a feeding-table, B, a rounding form or mandrel, D, rounding-rollers E, pressing-rollers F, a clamp, G G², and a backing-roller, I, arranged and operating substantially as herein described, for rounding and backing books by automatic machinery at one continuous operation, as set forth.
- To the above specification of our machine for rounding and backing books we have hereunto set our hands this 20th day of December, 1872.
